UNITED STATES PATENT OFFICE

2,308,888

HEATER

Henry J. De N. McCollum, Chicago, Ill.

Application August 9, 1939, Serial No. 289,108

9 Claims. (Cl. 126—110)

My invention relates generally to heaters, and more particularly to relatively small space heating units adapted for use in busses, trucks, and the like, and for the heating of small enclosures such as automobile service stations, etc.

It is among the objects of my invention to provide an improved space heater which is in the form of a self contained unit and may be operated independently of the engine of the vehicle and requires merely the supply of a liquid fuel, such as gasoline, and electric current.

A further object is to provide an improved liquid fuel burning heater in which a combustible mixture is supplied under pressure to a combustion chamber and in which the products of combustion are drawn from the heater by means of a suction blower.

A further object is to provide an improved unit type heater which is substantially noiseless in operation.

A further object is to provide an improved liquid fuel burning heater in which improved means are provided for obtaining a substantially complete atomization of the liquid fuel.

A further object is to provide an improved heater in which a single motor is utilized to supply combustible mixture under pressure to the combustion chamber, and to exhaust the products of combustion from the heater.

A further object is to provide an improved heater in which the richness of the mixture supplied to the combustion chamber is controlled by means responsive to the temperature of the exhaust from the heater.

A further object is to provide an improved heater having safety devices to stop the operation of the heater when the temperature thereof rises above a predetermined maximum value.

A further object is to provide an improved unitary heater which is relatively simple in construction and operation, which will be effective to deliver a large quantity of heat for its size, which may readily be controlled as to the rate of heat delivered, and which may be economically manufactured.

Other objects will appear from the following description, reference being had to the accompanying drawings, in which

Fig. 1 is a side elevational view of the heater;
Fig. 2 is a top plan view thereof;

Fig. 3 is a vertical cross sectional view taken on the line 3—3 of Fig. 2;

Fig. 4 is a horizontal sectional view taken on the line 4—4 of Fig. 1;

Fig. 5 is a fragmentary sectional view showing

a portion of the blower and the thermostatically operated valve for admitting additional air when the exhaust from the heater attains a predetermined temperature;

5 Fig. 6 is a transverse sectional view taken on the line 6—6 of Fig. 3;

Fig. 7 is a transverse sectional view taken on the line 7—7 of Fig. 4;

Fig. 8 is an elevational view of a modified form 10 of means for delivering liquid fuel to the heater;

Fig. 9 is a fragmentary sectional view taken on the line 9—9 of Fig. 8; and

Fig. 10 is a diagrammatic view of the heater including a modified form of fuel supply system 15 and the electrical wiring diagram therefor.

In general, the heater of my invention comprises an automatically operated pump for the liquid fuel, either mechanically or electrically driven, which supplies fuel to an auxiliary reservoir in which the level of the fuel is maintained

20 by a float operated valve and from which the fuel is drawn to a carbureting device by suction. The fuel mixed with atmospheric air in the carbureting device is supplied to a blower which assures substantially complete atomization of the liquid fuel, and discharges it under pressure into a combustion chamber. Within the combustion chamber is an electrically heated igniter which ignites the mixture and permits the addition of

25 auxiliary air to the burning mixture so as to insure complete combustion. The hot gases of combustion flow through a plurality of conduits forming a radiator or heat exchange device and into an exhaust manifold which leads to the inlet of a suction or aspirating blower. An electric motor driven fan circulates air from the enclosure to be heated over the heat exchange device or radiator. The fuel injection blower and the aspirating blower are driven by a common

30 motor, the speed of which may be manually controlled. The heater is provided with electrical control circuits whereby the supply of current to the electrically heated igniter is cut off after the heater has commenced operation, and for

35 cutting off the supply of current to the motor which drives the blowers whenever the radiator attains a temperature unsafe for continued operation. It is believed that with the foregoing general description of the invention, the more

40 detailed description which follows will be more readily understood.

45 Referring to Figs. 1, 2, 3, and 4, an automatic fuel pump 20 is mounted on the heater support 22 in any suitable manner, the fuel pump illustrated in the enumerated figures being electrical-

55

ly operated, being supplied with current through the conductor 24, the return path being through a suitable ground connection (not shown). The fuel pump 20 is supplied with gasoline through a conduit 26 and has an outlet conduit 28 which leads to an auxiliary reservoir 30 which may be of any suitable construction incorporating a float operated valve to maintain the fuel level therein uniform, or may be of a type having an overflow conduit 32 through which the surplus of the fuel supplied by the pump 20 may be returned to the main reservoir from which the pump 20 derives its supply of fuel. A conduit 34 leads from the auxiliary reservoir 30 to a carbureting device 36 (best shown in Fig. 4). The end of the conduit 34 leading into the auxiliary reservoir 30 may be of the construction disclosed in my co-pending application Serial No. 61,213, filed January 28, 1936, Patent No. 2,191,173, or in my co-pending application Serial No. 177,075, filed November 29, 1937. The latter application also discloses a suitable form of float controlled auxiliary reservoir.

Suction is induced in the outlet end of the carbureting device 36 by a blower 38 which comprises a housing 40 closed by a cover plate 42, the cover plate providing a bearing 44 for the hub 46 of an impeller or rotor, the blades of which are in the form of radial tubes 48 pressed into (and preferably welded) the hub 46. The hub 46 is non-rotatably secured to the rotating armature shaft 50 of an electric motor 52 which is suitably mounted on the heater support 22. The carbureting device 36, it will be noted from Fig. 4, has passageways for admitting atmospheric air, and a Venturi shaped passageway 54 for increasing the suction effective upon a nozzle 56 which is the effective termination of the conduit 34.

The mixture of the fuel and air supplied by the carbureting device 36 is radially ejected through the tubes 48 due to the centrifugal action. A substantial pressure is built up within the housing 40, the mixture being thus forced under pressure through an outlet tube 58 which is secured to the housing 40. The outlet tube 58 projects into a combustion chamber casting 60 which is suitably secured to a plate 62 mounted on the support 22. Within the outlet tube 58 is a heating tube 64, the inner end of which projects into a combustion chamber 66 formed in the casting 60 and closely adjacent a baffle plate 68 which, as shown in Fig. 6, has a plurality of notches 70 for the passage of the fuel mixture, and is likewise spaced from the wall of the combustion chamber by lugs 72 so as to provide a substantially complete annular passageway for the flow of the combustible mixture into the combustion chamber 66.

The combustion chamber casting 60 is enclosed in a housing 74 which is secured to the plate 62 by a nut 76 threaded over the end of the combustion chamber casting 60, and has an inlet port 78 registering with a corresponding opening formed in the plate 62 to admit atmospheric air thereto from the engine compartment of the vehicle, assuming that the heater is utilized for heating the passenger compartment of an automobile, bus or truck, and that the support 22 constitutes the dash of such vehicle. It will be understood, however, that the heater may be utilized for heating any enclosed space, and the support 22 may constitute a partition or wall of a room, or may be part of a housing and standard for the heater.

The housing 74 serves not only as a protection for the igniter hereinafter to be described, but

also serves as an insulator against the transmission of flame noise from the heater to the space being heated. The housing 74 may also constitute the support for a ring 80 which surrounds the end of the combustion chamber and forms a support for the manifold 82. The end of the manifold 82 is welded or otherwise suitably secured to the ring 80, and is spaced from the tubular projection 84 of the combustion chamber casting 60 to provide an annular passageway 86 through which air from within the housing 74 may flow freely into the manifold 82, as indicated by the arrow in Fig. 3.

It will be understood that ordinarily the mixture supplied to the combustion chamber will be relatively rich, so that complete combustion may not take place within the combustion chamber 66, and as a result the flame will extend into the manifold 82, combustion being supported by the auxiliary air admitted through the annular passageway 86. The flame and products of combustion within the manifold 82 are drawn through a plurality of radiating tubes 88 which connect the manifold 82 with an outlet manifold 90, the flow being as indicated by the arrows in Fig. 4. The outlet manifold 90 is connected by suitable conduit 92 with the inlet of a suction blower 94, the impeller of which is connected to the shaft 50 of the motor 52 and which is effective to create a partial vacuum in the conduit 92 and eject the products of combustion under pressure through a discharge conduit 96. The discharge conduit 96 may lead to any suitable outlet such as the flue of a chimney, if the heater is installed in a building, or, in case the heater is installed upon an automobile, the conduit 96 may exhaust directly to the outer atmosphere, or may be connected to the exhaust pipe of the vehicle.

The radiator formed by the manifolds 82 and 90, and the tubes 88 interconnecting these manifolds, is enclosed in a suitable housing comprising side walls 98, 100, 102, and 104, and having a bottom deflecting wall 106, the wall 106 serving to deflect air to the right (Fig. 3), through an outlet 108. A top 105, having a circular flanged fan receiving opening 107, completes the casing. Air is forced downwardly past the radiator by a fan 110 driven by an electric motor 112, the motor being mounted upon a suitable bracket support 114, which is welded or otherwise suitably secured to the manifolds 82, 90. A deflector plate 116 is mounted within the casing to prevent the fan from blowing cold air over thermostatically operated switch mechanisms hereinafter to be described.

As best shown in Figs. 4 and 10, a thermostatically operated switch mechanism 116 is secured to the end of the manifold 82 so as to be in heat conducting relationship therewith. The switch mechanism 116 comprises a switch arm 118 which is connected by a conductor 120 to a source of current 122, upon the closure of a control switch 124. The switch arm 118 carries a contact 126 which is normally in engagement with rigid contact 128, the latter being connected by a wire 130 with one terminal of igniter coil 132. The igniter coil, as illustrated in Figs. 3 and 10, may be made of a suitable resistance wire such as nichrome wire, and has one end grounded and the other end connected to an insulated terminal 134 to which the wire 130 is connected. The contacts 126 and 128 are normally in engagement so that upon closure of the switch 124, current will immediately flow to the igniter coil 132. After the manifold 82 becomes heated to a temperature approaching its

normal operating temperature, the thermostatic bi-metal arm 136 flexes to the left (Fig. 4), causing its contact 138 to engage a contact 140 carried by the contact arm 118. Upon engagement of these contacts 138 and 140, current may flow from the battery through the conductor 120 to the motor 112, causing circulation of air from the space to be heated downwardly past the radiator.

A safety switch mechanism 142 is secured to the outlet manifold 90 in heat conducting relationship therewith, the switch mechanism being generally similar to the switch mechanism 116 previously described, except that its bi-metal thermostatic arm 144 is preferably set so as to flex sufficiently to bring its contact 146 into engagement with the contact 148 carried by the center contact arm 150, at a temperature considerably higher than that at which the thermostatic bi-metal arm 136 operates. The switch mechanism 142 has a pair of contacts 152 which are normally closed and connect the switch arm 150 with a conductor 154.

The conductor 154 is connected to a contact arm 156 forming part of a rheostat including an adjustable resistance 158.

The rheostat is adapted to control the current flow to the motor 52, as well as to the electrically operated fuel pump 20. By adjustment of the position of the contact arm 156, the speed of the motor may be controlled, thereby controlling the rate of heat production of the heater unit, since the speed of this motor not only affects the rate at which the combustible mixture is supplied to the combustion chamber, but also determines the rate at which the gases of combustion will exhaust from the heater. It will be noted that the thermostatic bi-metal arm 144 of the switch mechanism 142 is electrically isolated, and the contacts 146, 148 thus do not complete any circuit. The thermostatic arm 144 functions only to open the contacts 152 whenever the manifold 90 approaches a dangerously high temperature, the switch thus constituting a safety cut-out for deenergizing the motor 52 if due to some unforeseen abnormal condition the radiator should become very hot.

After the heater has been in operation for some time, the housing of the blower 94 will, of course, become heated to some extent and transmit heat to a bi-metal thermostatic strip 162, one end of which is secured to the housing of the blower and the other end of which forms a valve closing the end of a conduit 164. The conduit 164 is connected to a passageway 166 formed in the cover plate 42 of the blower housing 40, and communicates with the interior of said housing through an inlet port 168, as best shown in Fig. 4. In order to assure rapid ignition of the combustible mixture supplied to the combustion chamber 66, when operation of the heater is initiated, it is desirable that the mixture be very rich. However, after normal combustion has started, the mixture may be made considerably leaner without disturbing normal combustion and, in fact, increasing the efficiency of combustion. Thus when the housing of the blower 94 becomes slightly heated after the normal combustion is initiated for a short time, the bi-metallic thermostatically operated valve 162 will open to admit additional air to the blower housing 40. This additional air is, of course, mixed with the mixture received from the carbureting device 36 and fed to the combustion chamber.

In Figs. 1, 2, 3, and 4, the fuel supply system for the heater is illustrated as including an elec-

trically operated gasoline pump which maintains liquid fuel at the required level in an auxiliary reservoir 30. In Fig. 10 the fuel pump 20 is illustrated as being connected directly to the carbureting device 36, in which case the fuel pump will either be of a construction in which the rate at which it discharges fuel is determined by the voltage of the current supply as governed by the rheostat 156, 158, or the fuel pump will incorporate a reservoir in which the fuel is maintained at substantially atmospheric pressure and at a substantially constant level.

In Figs. 8 and 9 I have shown a modified form of the fuel supply system which comprises a casing 174, the upper end of which is closed by a flexible diaphragm 176, the central portion of which is secured to a connecting rod 178. The rod 178 is connected to an eccentric strap 180 surrounding an eccentric 182 secured to the shaft 50 of the motor 52. The upward and downward oscillatory movement of the central portion of the diaphragm 176 causes the fuel to flow into the casing 174 from the pipe 184 which is connected to a standard fuel tank, and to discharge the fuel through a conduit 186. It will be understood that the casing 174 of the fuel pump will be provided with the necessary passageways and check valves to cause this result. Any suitable form of mechanically operated pump may be utilized, the construction illustrated in Figs. 8 and 9 being more or less diaphragmatic and representative of a variety of fuel pumps which are well known. The significant feature of the arrangement shown in Figs. 8 and 9, when used in the system shown in Fig. 10, is that the fuel pump is operated at a speed determined by the speed of operation of the motor 52 and that the displacement of the fuel pump may therefore be correlated with the fuel requirements of the heater when the motor 52 is operating at different speeds.

When the heater is placed in operation, the switch 124 is closed, thus connecting the conductor 120 to the "hot" side of the battery 122. Since the contacts 152 are closed at this time (it being assumed that the heater is at atmospheric temperature) current will be supplied through the conductor 154 to the rheostat 156, 158, which, as shown in Fig. 1, may be adjusted by means of a control knob 159. Depending upon the adjustment of the rheostat 156, 158, the motor will operate at a predetermined speed and create a partial vacuum in the Venturi shaped passageway 54 of the carbureting device 36, thus drawing liquid fuel directly from the fuel pump 20 (as shown in Fig. 10) or from the auxiliary reservoir 30 (as shown in Figs. 1, 2 and 4) into the blower housing. Particularly due to the construction of the blower, the partially atomized fuel supplied by the carbureting device 36 will be further broken up and more completely atomized in the course of the passage of the mixture through the blower. The mixture flowing under pressure developed by the blower will pass through the preheating tube 64 and be projected against the baffle plate 68, where the mixing and atomization will be rendered still more complete, the mixture then flowing into the combustion chamber 66 through the various apertures and slots formed in the baffle plate 68. Some of the fuel thus supplied will flow into the space beneath the igniter coil 132. The igniter coil will be supplied with heating current as soon as the switch 124 is closed, since as was assumed, the thermostatic switch mechanism 116

is at atmospheric temperature and its contacts 126 and 128 in engagement to complete the circuit from the battery through the conductor 130 to the igniter coil 132. The igniter coil is preferably made of sufficiently fine wire that it will heat to incandescence within a very short time under the applied voltage, so that shortly after the combustible mixture commences flowing into the combustion chamber, the igniter will be sufficiently hot to ignite the mixture and cause the propagation of a flame. This flame will project into the manifold 82 and be drawn, together with the products of combustion, through the tubes 88 into the manifold 90 under the influence of the suction generated by the suction blower 94.

After the heater has been in operation for a short period, the bi-metal thermostatic contact arm 136 will swing to the left (Fig. 4) and close contacts 138, 140, thus completing the circuit to energize the motor 112. The motor 112 drives the fan 110 circulating air from the space to be heated downwardly around the tubes 88 and manifolds 82, 90, ejecting the air in a generally horizontal direction from the outlet 108. As the manifold 82 becomes hotter, the thermostatic bi-metal contact arm 136 will flex still further to the left and open contacts 126, 128, thus cutting off the supply of current to the igniter coil 132.

After the heater has been in operation for some time, the housing of the suction blower 94 will become heated and as a result the bi-metal thermostatic valve 162 will commence opening, admitting additional air to the blower 38, and making the mixture more lean so as to assure complete combustion. Of course, throughout the operation of the heater, air will flow through the annular passageway 86, so that there will normally be a slight excess of air over that required for complete combustion. This excess of air is desirable to insure that no unburnt fuel or carbon monoxide is drawn through the heater and ejected from the exhaust pipe 96.

If for any reason the radiator should become excessively hot, the bi-metal thermostatic contact arm 144 of the switch mechanism 142 will flex to the left (Fig. 4) and separate the switch contacts 152, thus breaking the circuit which supplies the motor 52 as well as the electric fuel pump 20. When this circuit is opened, the heater will, of course, cease operation until the radiator has cooled to a safe operating temperature, whereupon the contacts 152 will again complete the circuit to the motor 52 and fuel pump 20. The completion of this circuit will, of course, result in the heater starting operation as previously described. There is however, the possibility that due to the fact that the bi-metal thermostatic contact arm 144 is constructed to open its associated contacts at a higher temperature than is required to cause the bi-metal contact arm 136 to operate its contacts, the contacts 126, 128 may separate when the heater has cooled to a temperature sufficient to permit the closure of the switch contacts 152. Under these latter circumstances the apparatus may operate for some short period without igniting the combustible mixture supplied to the combustion chamber, but this will not have any seriously disadvantageous effect because after a short time the thermostatic bi-metal contact arm 136 will be cooled by the mixture to a temperature which will result in its closure of the switch formed by the contacts 126, 128.

It has been found that a flame burning in a

5 combustion chamber and flowing into a space such as that provided by the manifold 82 has a tendency to produce a roaring noise. The noise is considerably reduced by the admission of additional air to the manifold 82 through the inlet passageway 86 and the conduction of noise from the manifold 82 to the outside atmosphere is hindered by virtue of the fact that the housing 74 encloses the combustion chamber and the only direct path for the travel of sound through air to the atmosphere is through the relatively small port 18 formed in the housing 74.

10 While I have shown and described particular embodiments of my invention, it will be apparent to those skilled in the art that numerous variations and modifications thereof may be made without departing from the underlying principles of the invention. I, therefore, desire by the following claims to include within the scope of my invention all such similar constructions and modifications by which substantially the results of my invention may be obtained utilizing substantially the same or equivalent means.

I claim:

- 25 1. In a unit heater, the combination of a combustion chamber, means to ignite a mixture of fuel and air supplied to said chamber, a fuel pump, a carbureting device connected to said fuel pump to receive fuel therefrom and admix air with said fuel, a blower for drawing the mixture of fuel and air from said carbureting device and forcing it into said combustion chamber, a radiator receiving the products of combustion from said combustion chamber, means for causing air to pass over the outer surface of said radiator, and suction means for withdrawing the products of combustion from said radiator and maintaining said radiator and combustion chamber under a partial vacuum.
- 30 2. In a unit heater, the combination of a combustion chamber, a blower for supplying a mixture of fuel and air under pressure to said combustion chamber, a radiator connected to receive the products of combustion from said combustion chamber, means for causing air to be heated to pass over the outer surface of said radiator a suction blower to withdraw the products of combustion from said radiator, and a common motor for rotating said blowers, said suction blower having a sufficiently greater capacity than said first-named blower to maintain the interior of said radiator at subatmospheric pressure.
- 35 3. In a unit heater, the combination of a combustion chamber, means to supply a combustible mixture to said chamber, a manifold for receiving products of combustion from said chamber, said manifold having an inlet end spaced from the end of said combustion chamber to provide an annular opening for the admission of atmospheric air to said manifold for admixture with the products of combustion, a casing surrounding said combustion chamber and sealed around the inlet end of said manifold, said casing having a restricted opening to the atmosphere formed therein, heat exchange means connected to said manifold, and suction means for withdrawing the products of combustion from said heat exchange means.
- 40 4. In a unit heater, the combination of a blower having an inlet and outlet, and having an auxiliary air inlet, means for supplying a combustible mixture to the inlet of said blower, a combustion chamber connected to the outlet of said blower, means to ignite the combustible mixture in said combustion chamber, heat radiating

means for receiving the products of combustion from said combustion chamber, a suction blower for drawing the products of combustion through said heat radiating means, and a thermostatically operated valve responsive to the temperature of the products of combustion withdrawn by said blower to admit air to said auxiliary inlet.

5. In a unit heater, the combination of a blower, means to supply a combustible mixture of liquid fuel and air to said blower, a combustion chamber connected to receive the combustible mixture from said blower, means to ignite the combustible mixture in said combustion chamber, a housing, forming a substantially closed chamber, around said combustion chamber and spaced therefrom, a tubular element receiving the products of combustion from said combustion chamber, said tubular element being spaced from the end of said combustion chamber to provide an auxiliary air admission passageway, said passageway communicating between the space within said housing and said tubular element, thereby reducing the noise created by the operation of said heater and means for creating a partial vacuum in said tubular element.

6. In a unit heater, the combination of a combustion chamber, electrical means for igniting a combustible mixture in said chamber, means for supplying a combustible mixture of fuel and air to said chamber, said means including an electrically operated fuel pump, a blower for forcing the combustible mixture to said chamber, a radiator connected to receive the products of combustion from said combustion chamber, means for causing air to be heated to pass over the outer surface of said radiator, an exhaust manifold, a suction blower connected to exhaust the gases of combustion from said exhaust manifold, a single electric motor for operating both of said blowers, and a manually operable rheostat common to said electric motor and said electric fuel pump for controlling the supply of electrical energy thereto, whereby a combustible mixture is supplied to said combustion chamber, and the interior of said radiator is maintained at sub-atmospheric pressure, at all normal speeds of motor operation.

7. In a unit heater, the combination of a combustion chamber, means to ignite a mixture of fuel and air supplied to said chamber, a fuel pump, a carbureting device connected to said fuel pump to receive fuel therefrom and admix air with said fuel, a blower for drawing the mixture of fuel and air from said carbureting device and forcing it into said combustion chamber means defining a substantially enclosed chamber having an air inlet, a duct for supplying a limited amount of air from said last-named chamber to the products of combustion from said combustion chamber, a variable speed motor driving said fuel pump and said blower, means for causing air to be heated to pass over the outer surface of said radiator a radiator receiving the products of combustion from said combustion chamber, and means for withdrawing the products of combustion from said radiator.
8. In a unit heater, the combination of a combustion chamber, means for supplying a combustible mixture of fuel and air to said combustion chamber, a radiator receiving the gases of combustion from said combustion chamber, means for removing said gases of combustion from said radiator, and means defining a substantially closed sound trap chamber, said radiator having an inlet end spaced from the end of said combustion chamber to provide an annular opening affording communication between said sound trap chamber and said gases of combustion.
9. In an internal combustion heater, the combination of a combustion chamber, means for supplying a combustible mixture of fuel and air to said combustion chamber, a heat exchange for receiving the gases of combustion therefrom, suction producing means for removing the products of combustion from said heat exchanger, means defining a sound trap chamber, and an inlet for admitting air to said sound trap chamber, said heat exchanger having an inlet end spaced from the end of said combustion chamber to provide an annular opening for permitting air to flow from said sound trap chamber to the gases of combustion leaving said combustion chamber.

HENRY J. DE N. MCCOLLUM.
